(57) **CLAIM**

The ornamental design for a veterinary saw, as shown and described.

DESCRIPTION

FIG. 1 is a bottom perspective view of a veterinary saw in accordance with our new design;

FIG. 2 is a top view thereof;

FIG. 3 is a bottom view thereof;

FIG. 4 is a side view thereof;

FIG. 5 is a side view thereof, for the side opposite that of FIG. 4;

FIG. 6 is a back view thereof; and,

FIG. 7 is a front view thereof.

The broken lines shown in the drawings illustrate portions of the veterinary saw that form no part of the claimed design.
